(57) CLAIM

The ornamental design for a book cover with handles, as shown and described.

DESCRIPTION

FIG. 1 is a perspective view of a book cover with handles showing my new design in a closed position;

FIG. 2 is a perspective view of the book cover in an opened
position;

FIG. 3 is a perspective view of the book cover in an opened
position;

FIG. 4 is a top plan view thereof;

FIG. 5 is a bottom plan view thereof;

FIG. 6 is a front elevational view thereof;

FIG. 7 is a rear elevational view thereof;

FIG. 8 is a right side elevational view thereof; and,

FIG. 9 is a left side elevational view thereof.

The portions shown in broken lines are included for illustrative purposes only and form no part of the claimed design.
